UNITED STATES PATENT OFFICE.

DONALD MERCER TERRY, OF NEW YORK, N. Y., ASSIGNOR TO WESTERN ELECTRIC COMPANY, INCORPORATED, OF NEW YORK, N. Y., A CORPORATION OF NEW YORK.

THERMIONIC PEAK VOLTMETER.

Application filed June 10, 1926. Serial No. 114,971.

This invention relates to voltage measurements, and more especially to the measuring of peak voltages.

This invention is an improvement over the 5 thermionic voltmeter disclosed in R. A. Heising Patent 1,232,919, issued July 10, 1917. In accordance with that invention the input circuit of an electron discharge device is adjusted through a slide wire resistance to reduce the plate or output current to zero and the potential drop across the slide wire resistance is measured by means of a voltmeter. The voltage to be measured is then impressed on the input circuit and the 10 resistance again adjusted to reduce the output current to zero. Another measurement is then made of the voltage drop across the resistance and the difference of these voltage drops is computed to obtain the voltage 15 to be measured. It will be seen that a direct indication of the peak voltage cannot be obtained by this method.

An object of the present invention is to 20 measure a peak voltage between two points of an electrical network without taking current from that network and without introducing frequency errors.

Another object of the invention is to directly and accurately indicate the value of the 25 peak voltage to be measured.

In accordance with this invention, an electron discharge device is provided with separate sources of potential for adjusting the normal output current of the device to an 30 optimum operating value and for reducing the space current to this operating value when a voltage to be measured is impressed upon the input circuit, so that the voltage can be directly and accurately determined 35 without calculation.

This invention can be more readily understood by reference to the following detailed description in connection with the drawing which shows diagrammatically one embodiment 40 of the invention.

Referring to the drawing, the peak voltmeter comprises an electron discharge device 1 having input conductors 2 and 3, upon which is impressed the voltage it is desired 45 to measure. This device consists of an electron emitting cathode or filament 4, an anode 5, and a control electrode or grid 6, enclosed in an evacuated glass vessel. The cathode 4

is connected externally to a heating circuit including a battery 7, an adjustable resistance 8, and an ammeter 9. This ammeter indicates the current flowing in the filament and serves as a means for maintaining the filament at the most efficient operating temperature. An arm 10 of a gang switch 11 opens and closes the filament circuit. The grid 6 is connected to conductor 2 of the input circuit and conductor 3 is connected through switch 12, conductors 13 and 14, assuming all adjustable contacts are at zero, to one side of the filament 4, thus completing the input circuit. The output circuit of the device comprises anode 5, battery 15 and milliammeter 16, which is connected to the common point of the filament 4. 55 A source of voltage 17, such as a battery, is provided in the input circuit to impress a negative potential on the grid 6 of the discharge device 1. The movable contact 18 cooperating with fixed contacts 18^a provides 60 means for varying the voltage; and the resistances 19, in alternate leads of the contacts make it possible to obtain this change of voltage without opening the grid circuit or short circuiting the battery 17. This arrangement will be hereinafter designated as 65 the coarse adjustment of the grid voltage. Another source of voltage 20 is connected in the input circuit through arm 21 of switch 11, and adjustable resistance or potentiometer 22, to provide a fine adjustment of the grid voltage. A voltmeter 23 is connected across 70 these two sources of voltages to indicate the value of the voltage measured. A multiplier 24 comprising a variable switch and different 75 values of resistances is provided in the voltmeter circuit to cover a large range of voltages which may be measured in accordance 80 with this invention.

A battery 25 connected to an auxiliary potentiometer 26 through arm 27 of gang switch 11, is utilized to maintain the potential of the anode at a desired operating point on the characteristic curve of the discharge device as will be further explained herein- 85 after. The potential 25 is not indicated on the voltmeter 23 and is used solely to adjust the plate current under normal conditions, i. e. with no external source connected to input conductors 2 and 3. A resistance 28 and 90 a switch 29 are connected across the input 100 105

conductors 2 and 3 to provide a shunt path of high resistance when the voltage peak to be measured is taken across a circuit in which a condenser is in series with the line. Otherwise, this resistance should be removed from the circuit, since, if the impedance of the circuit across which the peak voltage is to be measured should be of as high an order of magnitude, the shunt resistance would afford 10 an unnecessary load which would probably lower the voltage to be measured.

The operation of the peak voltmeter is as follows:

The filament circuit is closed by the arm 10 15 of gang switch 11 and the filament current adjusted by the resistance 8, until the desired value is indicated on the ammeter 9. Assuming all the variable adjustments in the input circuit are at zero, a space current will be indicated on the milliammeter 16. With a suitable type of tube this space current may be of the order of 1.5 milliamperes. It has been found, that if the space current is reduced to a recommended zero operating point of 0.1 25 milliampere, a wide range of peak voltages can be measured with accuracy and sensitivity.

The plate current is adjusted and maintained at the recommended zero operating 30 point of 0.1 milliampere by the battery 25 and the adjustable potentiometer 26, which impresses a negative potential on the grid sufficient to reduce the space current to the recommended zero operating point of 0.1 milliampere and change the indication on the milliammeter 16. When this adjustment is completed, the alternating voltage source to be measured is connected to the conductors 2 and 3. The effect of this voltage source is to correspondingly increase the plate current to a 35 value higher than the optimum space current. This increase is overcome and the plate current maintained at its normal operating value of 0.1 milliampere, by advancing the movable contacts of the coarse adjustment of potential 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890

alternating current peak voltage measurements it is necessary that the peak voltmeter be calibrated, to correct the inherent error which results from the fact that the average value of plate current from rectified peaks 70 must be less than the maximum current of the cut-off peaks when the device is operated above the zero point of its characteristic curve. It is desirable to operate the discharge device above the zero point, since in lowering 75 the operating point, a point is soon reached, even with a very sensitive plate-current meter, where the inaccuracy of the grid potential adjustment can result in a large observational error. With the peak voltmeter of this invention an ordinary voltage measuring instrument can be used and will be comparable in range with the magnitude of the voltages to be measured.

The invention is adaptable for measuring a 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890

What is claimed is:

1. A peak voltmeter comprising an electron discharge device having input and output circuits, a current indicating device in said output circuit, terminals for impressing upon said input circuit a voltage to be measured, a source of potential in said input circuit for maintaining the normal current in said output circuit at a definite operating value, a second source of potential in said input circuit for reducing the current in said output circuit to said operating value when the voltage to be measured is connected to said terminals, and means for directly indicating the value of the potential of said second source to give the value of the voltage to be measured.

2. A peak voltmeter comprising an electron discharge device having a cathode, a control electrode and an anode, input and output circuits for said device, a current indicating device and a source of potential in said output circuit, terminals for impressing on said input circuit a voltage to be measured, a variable source of potential in said input circuit for adjusting the normal operating current of said device to an optimum operating value, a second variable source of potential for adjusting the output current of said device to said operating value when said terminals are connected to a voltage to be measured, and a measuring instrument for directly indicating the value of the potential of said second source to give directly the value of the voltage to be measured.

3. The method of determining the magnitude of a voltage of an alternating current which comprises applying steady potentials 130

to the input and output circuits of a vacuum tube, impressing a negative potential on the control member of said tube to reduce the space current flowing in the output circuit to a low finite value, applying the alternating current voltage to the input circuit of said tube, impressing a second voltage on the control member of said tube to oppose the alter-

nating current voltage, reducing the space current to said finite value, and measuring ¹⁰ the magnitude of said second voltage.

In witness whereof, I have hereunto subscribed my name this 3rd day of June A. D., 1926.

DONALD MERCER TERRY.
